Primary Examiner — Holly E Thurman*Assistant Examiner* — Altaira J Swangin(74) *Attorney, Agent, or Firm* — Sterne, Kessler, Goldstein & Fox P.L.L.C.(57) **CLAIM**

The ornamental design for an electronic device, as shown and described.

DESCRIPTION

FIG. 1 is a top front perspective view of an electronic device showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top rear perspective view thereof.

The dashed broken lines in the figures show portions of the electronic device that form no part of the claimed design.

1 Claim, 8 Drawing Sheets---
